UNITED STATES PATENT OFFICE.

EMORY B. DUNKEL, OF LUCKNOW, AND FRANK S. BOWMAN, OF HARRISBURG,
PENNSYLVANIA.

TRAIN-PIPE COCK AND OPERATING MECHANISM THEREFOR.

1,079,847.

Specification of Letters Patent. Patented Nov. 25, 1913.

Application filed October 28, 1911. Serial No. 657,253.

To all whom it may concern:

Be it known that we, EMORY B. DUNKEL and FRANK S. BOWMAN, citizens of the United States, residing at Lucknow and 5 Harrisburg, respectively, in the county of Dauphin and State of Pennsylvania, have invented new and useful Improvements in Train-Pipe Cocks and Operating Mechanism Therefor, of which the following is a specification.

The invention relates to a train pipe cock used now as angle cocks for air brake systems, and more particularly to the class of angle cocks, and operating mechanism therefor.

The primary object of the invention is the provision of a cock of this character in which the handle thereof is disposed beneath the same and may be readily and quickly 15 operated for the opening or closing of the cock, without requiring an operator going between the cars for this purpose, thereby avoiding the possibility of injury or the loss of life, resultant therefrom.

Another object of the invention is the provision of a train pipe cock in which the handle thereof will be sustained or locked in its open or closed position, so as to prevent the possibility of the accidental shifting of 20 the handle by reason of shocks and jars incident to the travel of a train, the cock being readily and easily set in either opened or closed position from both sides of the car, thereby avoiding the necessity of the 25 operator going between the cars when manipulating the cock.

A further object of the invention is the provision of a device of this character which is simple in construction, thoroughly reliable 40 and efficient in operation, and inexpensive in manufacture and installation.

With these and other objects in view, the invention consists in the construction, combination and arrangement of parts, as will 45 be hereinafter more fully described, illustrated in the accompanying drawings, and pointed out in the claim hereunto appended.

In the drawings:—Figure 1 is a fragmentary end elevation of a car, showing the train pipe cock mounted thereon and the operating mechanism therefor constructed in accordance with the invention. Fig. 2 is a fragmentary bottom plan view of a car body, 50 showing the train pipe cock and operating mechanism in position thereon. Fig. 3 is a

fragmentary side elevation. Fig. 4 is an enlarged side elevation of the train pipe cock. Fig. 5 is a bottom plan view thereof, showing the handle in shifted position by dotted lines. Fig. 6 is a detail vertical longitudinal sectional view through the handle, showing the locking pin in side elevation. Fig. 7 is a vertical transverse sectional view through a portion of the body of the cock and the handle. Fig. 8 is a perspective view 65 of one of the hangers for the operating mechanism. Fig. 9 is a perspective view of one of the levers of the operating mechanism. Fig. 10 is a side elevation of a slight modification of a hanger for the operating 70 mechanism.

Similar reference characters indicate corresponding parts throughout the several views of the drawings.

Referring to the drawings by numerals, 5 75 designates generally a portion of the body of a freight car, having mounted on its end sill 6 a coupler head 7, and a bracket 8 for the brake rod 9, as usual. Also suitably mounted beneath the sills of the car, in suitable brackets, is the train pipe 10 provided at each end with a cock, presently described.

The train pipe cock comprises a straight body 11 having rotatably fitted therein the valve, with stem 12, the same being held 85 against displacement therein by means of a cap 13, and connected to this valve stem is the handle 14, the same being formed with a vertical socket 15 in its thickened portion 16, the socket 15 being closed at its open end 90 by means of a removable screw plug 17, and working within the socket is a locking pin 18, the same also working through a suitable guide opening 19 opening through the inner face of the handle and communicating with 95 the said socket 15, the pin being designed to engage in beveled indentations or notches 20 formed in the flattened face 21 of the body, so that the handle 14 will be locked in its thrown position for either opening or closing the train pipe cock.

Formed on and projecting outwardly from the flattened face of the body 11, at diametrically opposite points, are stop lugs 22, against which is adapted to contact the handle 14, when being thrown to either open or closed position.

Suitably fastened to the end sill 6 of the car body 5, on opposite sides of the point of disposition of the angle cock, are hangers, 116

each comprising a rod 23, the same being bent at one end to form reversely disposed open loops 24, with which are engaged the fasteners for securing the hangers to the end 5 sill, the loops serving as shoulders to prevent swaying of the hanger while the opposite end of the rod is formed with a guide eye 25, and through these eyes of the said hangers are passed rods 26, the inner ends 10 of which are suitably connected to the free end of the handle 14, while their outer ends project a convenient distance spaced from the planes of the sides of the car, and terminate in handles 27 to be grasped by an 15 operator, so that upon pulling or pushing upon one of the rods 26 the handle 14 of the angle cock may be shifted for the operating of the train pipe cock. The push rod 26 is to be pushed or pulled until the handle 14 20 comes in contact with the stop lug 22, thus when the handle 14 is pushed or pulled to meet the inside lug 22, the valve is opened and when the handle 14 is pushed or pulled to meet the lug 22 on the outside of the body 25 of the cock, the valve is closed.

By reason of the fact that the handle of the train pipe cock is operated beneath the train, numerous accidents and troubles which arise from protruding bolts coming in 30 contact with the handle and closing the same, thus shutting off air in the remainder of the train, will be avoided, the handle being entirely out of danger.

In Fig. 10, there is shown a slight modification of hanger for supporting the rods 26, wherein there is shown a rod 28 having a threaded end 29 provided with jam nuts 30 which permit the mounting of the said rod 28 upon the sill of a steel freight car,

the opposite end of the rod being formed 40 with a guide eye 31, through which is passed the rods 26.

From the foregoing, taken in connection with the accompanying drawings, it is thought that the construction and operation 45 of the invention will be readily understood, without requiring a more extended explanation.

What is claimed is:

A train pipe cock including a body and a 50 turning plug mounted therein, said turning plug having a stem at its lower end extending below the under side of the body and a handle attached to said stem, said body having stop lugs, on its lower side, on opposite 55 sides of the stem and in the path of the handle and also having spaced beveled notches in its lower surface, between said stop lugs, the bevels of said notches extending in opposite directions and said notches being 60 deepened at their outer sides, and a spring pressed pin mounted in the handle and having a terminal rounded end to cooperate with said notches and lock the handle in engagement with the stop lug and permit 65 movement of the handle in the opposite directions under sufficient pull in combination with means connected to the handle and projecting in both directions and beyond, to permit operation of the handle from opposite points relatively remote therefrom.

In testimony whereof we affix our signatures in presence of two witnesses.

EMORY B. DUNKEL.
FRANK S. BOWMAN.
